UNITED STATES PATENT OFFICE.

EMORY STOCKWELL, OF STAMFORD, CONNECTICUT, ASSIGNOR TO THE YALE & TOWNE MANUFACTURING COMPANY, OF SAME PLACE.

BURGLAR-PROOF SAFE.

SPECIFICATION forming part of Letters Patent No. 286,088, dated October 2, 1883.

Application filed April 14, 1883. (No model.)

To all whom it may concern:

Be it known that I, EMORY STOCKWELL, of the town of Stamford, in the county of Fairfield and State of Connecticut, have invented 5 certain new and useful Improvements in Safes, of which the following is a specification.

My invention is principally designed as an improvement in burglar-proof safes, but is useful for a high class of fire-proof safes.

10 Burglar-proof safes, as now most commonly constructed, consist of a series of metal plates of iron and steel, or other hard and soft metals, which are bolted together in various methods. Many weaknesses occur in this method of manufacture, owing to the fact that in large plates it is almost impossible to have perfect bearing-surfaces throughout, and equally difficult to harden large plates, so that when the large plates, which are usually of iron, are bolted to 15 the plates consisting of steel and iron, the iron plates cannot be drawn down so close to the steel and iron plates as to come in absolute contact throughout. Now, the steel and iron plates are necessarily, or at least usually, made narrow, so that in a safe of considerable size it is built up of a great number of plates, which 20 of course necessitates a great number of joints. These safes, therefore, being made of a large number of separate pieces bolted together, allow of various modes of attack which depend 25 on the gradual destruction of portions of the safe at one time. The different layers of the safe, not being in close contact throughout, may be attacked by means of drawing the temper 30 of the hard plates by any convenient application of heat, and then by drilling a hole through the plate from which the temper has been drawn. After one plate has been overcome 35 the next one can be attacked in turn until a hole is made completely through the safe. After the hole is through it is obviously a matter of a few moments to shatter the safe by means of an explosive introduced into the inside 40 through the hole. But the most serious weakness of this class of safes arises from the most recent method of attacking safes—namely, by the explosion of any powerful, quick explosive—such as nitro-glycerine, or any of its compounds—against the outside of the safe.

The effect of such an explosion on the outside 50 of a safe is not only to break the bolts with which the explosive is immediately in contact, but it also causes the door or wall of the safe to spring or bulge inward with great force. As will be readily perceived, the effect of this 55 spring of the plates is to cause every plate to move sidewise with reference to every other plate and to snap off the bolts which hold them together. The final result, therefore, is to 60 separate all the plates from each other, the bolts being broken, and this being so the door or wall of the safe will simply fall to pieces.

To avoid some of the difficulties of the built-up safes, as above stated, various styles of safes have been made, some of them of cast or 65 chilled metal, and some of them of cast metal surrounding a basket-work of wrought metal. The weakness of safes made entirely of hard cast metal is that by repeated blows this metal might be broken up, so that it will fall apart in 70 pieces. Even where a wrought-iron basket-work is inserted in the metal, the cast portion may be broken into pieces and fall away, and thus leave only the wrought-iron basket-work as a protection.

Generally stated, my improvement consists 75 in a solid safe of cast drill-proof material protected throughout its entire outside and inside surface by a soft and tough metal armor. This armor, both inside and out, is preferably to be 80 fused into one piece with the drill-proof portion of the safe, so that when completed the safe will be one solid piece of metal with a soft and tough exterior and interior, and a hard drill-proof middle.

To construct one of my improved safes the 85 inside armor is first cast, and this armor is then placed on the inside of the core which is used to cast the outside armor, the core being made of the proper size to provide for the desired thickness of hard drill-proof metal between the inside and outside armor. The outside armor is then cast around the inside armor and the core removed. Both the inside and outside armor are then malleableized, so 90 as to be of the required degree of ductility. Then the inside armor is held in the desired 95 relation to the outside, so as to be at the proper

distance from it at all points, and the hard drill-proof metal is poured in between the two.

In the accompanying drawings, illustrating my invention, Figure 1 is a front elevation of my improved safe without a door; and Fig. 2 is a horizontal section of the same, showing a door in place and closed.

A indicates an inside soft-metal armor, B an outside soft-metal armor, and C a body of hard-metal armor between the said soft-metal parts, or it may be fire-proof material. The number of layers or strata of alternate hard and soft bodies of armor may be varied at will; but a good safe can be made by using three layers, A, B, and C.

D indicates studs, which may be used, if desired, to secure the hard and soft armor together.

20 In Fig. 2 is shown in section an inside safe or cash-box, composed of the hard-metal armor E and the inside soft-metal armor, F, cast in one with the safe-body and in a similar way.

A shelf, S, is shown in Fig. 1 as cast in one piece with the inside soft-metal armor, A. There may be more shelves, or vertical partitions may be formed in this way integral with the safe itself, and contributing directly to its strength and invulnerability. An extra 30 outside soft armor, G, is provided in front of the cash-box, and H indicates a place for bolt-work.

K indicates the soft-metal edges of the doors L and M, which are cast in one piece with the outside and inside soft armor of the respective outside and inside doors.

In preparing the hard drill-proof metal for casting it is best to have a considerable surplus over the amount actually required to fill 40 the space it is to occupy in the safe-wall, and also to pour it with a head and an overflow. The object of having a surplus of metal is that the molten metal may be kept running through the safe until the sides of the inside and outside armor next to the molten metal shall become fused with it. When this point is reached, the flow is stopped and the metal allowed to cool, when, as above stated, the safe will be 50 one solid mass of metal, with soft and tough exterior and interior and hard and drill-proof middle. If preferred, the outside and inside armor may be cast with studs or bolts projecting into the hard metal, as shown in the drawings. The object of this is to make, if 55 possible, a more perfect connection between the armor and the hard metal. In cases where studs are used, the drill-proof metal may be poured without a head or overflow, because, even if no fusion takes place, the armor and 60 the drill-proof metal will be firmly attached by means of the studs.

It will be observed that by this construction all the weaknesses of the safes above set forth are completely avoided. It will be impossible 65 to attack this safe by drilling, because the temper of the interior cannot be drawn. Nor

will explosives have any effect upon it, because there are no parts of the safe which can be broken apart, and even if the door or walls should be sprung enough to crack the interior 70 it would be held in place by the inside and outside armor, and would be practically as secure as before.

In constructing the door I preferably make it with thin armor all around its edges of the 75 same material as the front and back—that is, the door is practically a box of soft and tough material, filled with a hard drill-proof material, so that the inside armor is attached to the outside armor, and cannot be peeled off 80 from the drill-proof metal. The advantage of this is, when the bolt-work is attached to the interior of the door it is held on by the strength of both the inside and outside armor and cannot possibly be detached from the 85 door.

The surface of the jamb will consist of the edges of the inside and outside armor, and also of the drill-proof middle. The shape of the door is immaterial so far as this invention 90 is concerned; but whatever may be its shape, the door and jamb will be ground so accurately that there will be an air-tight fit between them, so as to prevent the introduction of an explosive, and also so as to obviate the necessity of the ordinary packing, which can be 95 readily destroyed.

The form of the safe is also immaterial to this invention. It may be cast with great facility in any form desired, which gives it another great advantage over safes built up from plates. To avoid injurious strains in the safes, due to the contraction of the metal in cooling, I would preferably make the corners rounding, and also make the sides and the door of 105 the safe slightly rounding. This construction will not only avoid initial strains, due to the contraction of the metal, but will also give the greatest strength where it is most needed to resist the attacks of burglars. 110

A further great advantage of this construction is that the inside boxes for the safe, commonly known as "cash-boxes," may be cast in one piece with the inside armor, and also the shelves on the inside of the safe may be cast 115 in one piece with the inside armor. This construction will give immense strength and stiffness to the whole construction, making it practically one solid block of metal.

In the drawings no bolt-work is shown, because the form of bolt-work is not material to this invention, any kind desired being equally applicable. Nor do I show any spindle passing through the door, as that is also immaterial to this invention. A convenient 125 method of introducing a spindle would be by casting a spindle-sleeve in connection with the inside and outside armor, in the method set forth in my application for a United States Patent No. 86,424, filed complete February 130 27, 1883.

The construction above shown is applicable

to fire-proof safes of a high grade of excellence by constructing the inside and outside armor in the method above described, and then filling the space between them with any of the 5 well-known fire-proof materials. The outside armor, being without seam, would make the safe much stronger to resist the blows of falling bodies or the concussion of the safe itself falling from a great height in a building. For 10 fire-proof safes the outside armor may be in more than one piece, and the inside lining may be made as desired.

I am aware that it is not new to secure plates of different kinds of metal together by casting 15 one plate against the other, so as to fuse them together. I am also aware that it is not new to unite two plates of metal by means of studs or pins secured into one plate and projecting into the mold into which is to be cast the other 20 plate, forming it round the studs or pins. I am also aware that it is not new to form the walls of safes and of safe-doors of alternative layers of wrought metal and of cast metal, the cast-metal layers being joined either with or 25 without fusing to the wrought metal. I am also aware that it is not new to cast a safe body or shell of a single piece of metal; and I do not claim any of these things *per se*.

What I claim, and desire to secure by Letters Patent, is—

1. A safe composed of an inside and outside armor of ductile cast metal, with a hard drill-proof metal cast between them, substantially as described. 30
2. A door for a safe, composed of a surrounding wall or box of ductile cast metal, with an inside of hard cast metal, substantially as described. 35
3. A safe composed of inside and outside armor of ductile cast metal, with hard cast 40 metal between them, and with one or more inside chests, said chest or chests being cast in one piece with the inside armor of the safe, substantially as described.
4. A safe composed of inside and outside 45 armor of ductile cast metal, with hard cast metal between them, with one or more shelves cast in one piece with the inside armor, substantially as described.

In testimony whereof I have hereunto subscribed my name this 21st day of March, A. D. 50 1883.

EMORY STOCKWELL.
